(57) **CLAIM**

The ornamental design for a CNC fixture, as shown and described.

DESCRIPTION

FIG. 1 is a front perspective view of a CNC fixture showing my new design;

FIG. 2 is a back perspective view thereof;

FIG. 3 is a front perspective view thereof mountably configured with a vise;

FIG. 4 is a front perspective view thereof showing a center hub rotatably re-positioned from an upright orientation;

FIG. 5 is a front elevational view thereof;

FIG. 6 is a back elevational view thereof;

FIG. 7 is a left side elevational thereof;

FIG. 8 is a right side elevational view thereof;

FIG. 9 is a top plan view thereof; and,

FIG. 10 is a bottom plan view thereof.

The evenly-spaced broken lines in the drawings depict portions of the CNC fixture that form no part of the claimed design. The long-dash, short-dash broken lines shown in FIG. 3 depict a vise that forms no part of the claimed design.
